UNITED STATES PATENT OFFICE.

ARTHUR WILLIAMS McCURDY, OF TORONTO, CANADA, ASSIGNOR TO EASTMAN KODAK COMPANY, OF ROCHESTER, NEW YORK, A CORPORATION OF NEW YORK.

PHOTOGRAPHIC DEVELOPING APPARATUS.

No. 823,623.

Specification of Letters Patent.

Patented June 19, 1906.

Application filed April 20, 1904. Serial No. 204,081.

To all whom it may concern:

Be it known that I, ARTHUR WILLIAMS McCURDY, a subject of the King of Great Britain, residing in the city of Toronto, Dominion of Canada, have invented certain new and useful Improvements in Photographic Developing Apparatus; and I do hereby declare the following to be a full, clear, and exact description of the same, reference being had to the accompanying drawings, forming a part of this specification, and to the reference characters marked thereon.

My present invention relates to photographic developing-machines, and particularly to that class employed for developing photographic negatives or prints arranged upon strips or ribbons of flexible sensitized material and embodying generally a casing in which a spool or cartridge of sensitized material may be placed and the film or coating thereon developed and washed without exposure to the light.

My invention has for its object to provide a casing or receptacle comprising two chambers which are capable of being closed to exclude the light, one of which comprises a holding-compartment having a shaft or reel therein adapted to contain a flexible apron or support, previous to the developing operation, and the other forming a developing-compartment having an operating shaft or reel on which the apron or support may be wound from its supporting-shaft, together with the sensitized material, into said developing-chamber and moved continuously through the developing agents or solutions contained therein.

My invention has for its further object to provide a simple and effective holder that is capable of being adjusted to contain spools or cartridges of various sizes.

To these and other ends my invention consists in certain improvements and combinations of parts, all as will be hereinafter more fully described, the novel features being pointed out in claims at the end of the specification.

In the drawings, Figure 1 is a side elevation of the developing-machine constructed in accordance with my invention. Fig. 2 is a vertical sectional view on the line 2^x 2^x of Fig. 1, showing the apron or support arranged in the operative position in the de-

veloping compartment or chamber. Fig. 3 is a similar view on the line 3^x 3^x of Fig. 2. 55 Fig. 4 is a cross-sectional view similar to Fig. 3, showing the parts of the casing in the open position and illustrating the apron in its holding-compartment. Fig. 5 is a cross-sectional view on the line 5^x 5^x of Fig. 3, showing the spool or cartridge holder. Fig. 6 is a detail plan view of one end of the apron or support. Fig. 7 is a longitudinally-sectional view of a developing-machine embodying a modification of my invention. 65

Similar reference characters in the several figures indicate similar parts.

A developing-machine constructed in accordance with my invention embodies a casing comprising two chambers A and B, constituting, respectively, a compartment in which the developing operations or treatment of the sensitized material is carried on and a compartment containing the apron or support which carries said material when it is 75 not in use and in which it may be arranged to enable the operator to conveniently transfer it to the developing-chamber.

In the drawings the chamber A is shown as formed by a casing, preferably constructed 80 of sheet metal, the forward and rear ends thereof being indicated by 1 and 2, respectively, between which extend the sides 3, curved, as shown particularly in Fig. 3, to form a semicircular bottom which approximately conforms to the apron or support when the latter is wound upon the operating-shaft in the developing-chamber. The casing is held in an upright position by means of the feet or base portions 4. The chamber B, 90

formed by the end portions 11 and 12 and the wall 13, which may also be rounded, as shown in Figs. 3 and 4, forms a cover or closure for the casing, and for convenience in operation the parts are hinged at one side, as indicated 95 at 5, and their meeting edges are formed to overlap by providing one of the parts with an outwardly-projecting tongue 6 and the other with a corresponding groove or depression 7, coöperating therewith, to exclude 100 rays of light from the interior of the casing when the parts are closed in the normal position, as shown in Figs. 1, 2, and 3.

The winding or operating shaft (indicated by 8) extends longitudinally of the developing-chamber A, and its inner end is journaled 105

in a boss or extension 9, formed on the rear side portion 2, while its outer end is journaled in a gland or stuffing-box 10 and is provided with an operating arm or handle 15. The longitudinal movement of the shaft is prevented by the reel heads or hubs 16, arranged thereon in juxtaposition to the end portions 1 and 2 of the casing and secured to the shaft by pins or fingers 17, arranged at the end of a bar or member 18, extending longitudinally of the shaft in proximity thereto and adapted particularly to form a securing device beneath which the end of a strip of sensitized material or the usual opaque covering thereon may be engaged. The hubs 16 are provided with fingers or projections 19, adapted to coöperate with engaging members 21, arranged at the end of the apron or support 25, as will be more fully described hereinafter. Hubs 26, similar to those just described and provided with fingers or projections 27, are rigidly secured to the supporting-shaft 20 and are adapted to coöperate with engaging members or loops 28, arranged on the opposite end of the apron or support and permitting the latter to be wound into the receiving-chamber, as shown in Fig. 4, and when drawn therefrom and unwound from the supporting-shaft 20 to be automatically disengaged from the shaft, thereby permitting the apron to be drawn into the developing-chamber and rotated continuously therein for the desired length of time.

The apron or support 25 is constructed of thin, flexible, and preferably transparent material, such as celluloid, of a length somewhat greater than the standard lengths of film or sensitized material adapted to be treated in the apparatus, and at its edges it is provided with filling-pieces 29, secured by lines of stitching, and formed in the apron adjacent the filling-strips are apertures 30, adapted as the apron is wound upon itself to permit the developing agents or materials to flow freely between the adjacent convolutions thereof. At its ends the apron is looped over the cross-bars 35 and 36, carrying the engaging devices or loops 21 and 28, and to accommodate these bars so that the apron will be wound symmetrically around the shafts 8 and 20 the reel-hubs 16 and 26 are provided with notches, as shown, located in rear of the fingers or projections.

An apparatus of this character is adapted particularly for developing photographic negatives or prints made upon strips or ribbons of sensitized material wound upon spools and having a protecting envelop or cover of opaque paper and designated generally as "cartridges," and as there are different widths of sensitized material, so that the cartridges vary in length, it is the desideratum to provide a holder consisting of few parts and which may be easily adjusted to accommodate them. Extending outwardly from

one side of the casing and preferably connected to the chamber A is a recess which is adapted to receive the spools or cartridges. Arranged exteriorly of the recess and in proximity to the top of the chamber is a rod or bar 37, constituting a frame on which is mounted a longitudinally-movable arm 38, having the depending end extending into the recess and provided with a pin 39, forming a journal for one end of a spool or cartridge. The arm is also formed with a foot or extension 41 and the ear or finger-piece 42, adapted to engage the sides of the chamber and the recess, as shown in Fig. 4, to prevent the rotary movement of the arm on the rod, although permitting it to be freely adjusted thereon, the finger-piece forming a projection by means of which the arm may be easily manipulated. The journal or support for the other end of the spool or cartridge is formed by a pin 43, arranged in axial alinement with the pin 39 and provided with the head 44, adapted to be held in frictional engagement with the spool by means of a coil-spring 45, supported in a sleeve 50, and also provided with an outer operating-head 51, whereby the pin may be retracted when it is desired to remove the spool from the holder. This arrangement of the parts is simple and effective, for it will be seen that to adjust the holder to receive a spool or cartridge of any desired size it is only necessary to shift the arm 38 longitudinally on the rod or bar 37, and as the pressure of the spring 45 exerted on the spool is sustained by the end of the adjustable arm and at a point removed from the bar 37 the arm will be securely clamped by its frictional engagement therewith.

In Fig. 7 I have illustrated a modification of the apparatus which also embodies my invention. In this form of this device the chambers A and B are arranged side by side in a single casing 52, having the open top adapted to be closed by a cover 53. The walls of the casing are preferably curved, as shown, and the chambers are separated by a partition 54, the lower end of which is also curved to form a semicircular bottom for the developing-chamber A. The upper end of the partition is terminated below the top of the casing to form a passage connecting the two chambers. The latter are provided with the shafts 8' and 20', respectively, having the hubs 16' and 26', provided with fingers adapted to coöperate with the engaging devices at the ends of the apron or support 25'. The cartridge or spool holder is similar to the holder heretofore described and embodies the bar or frame 37', on which is mounted the adjustable arm 38'.

To place the apparatus in condition to perform a developing operation, the apron or support 25 is wound within the holding-chamber B by first attaching the engaging device or loops 28 at the outer end of the

apron in engagement with the projections or fingers 27 and revolving the shaft 20, as shown in Fig. 4. The spool or cartridge may then be secured in the holder, as shown in Fig. 5, and the end of the covering or light-excluding envelop attached to the winding or operating shaft 8 by slipping it beneath the bar 18. The shaft 8 may then be rotated to withdraw the extended end of the envelop or cover, and to this end the cover is preferably provided with the word "Stop," which indicates to the operator that the contents remaining upon the spool are to be carried by the apron or support. The operator then attaches the engaging devices or loops 21 on the end of the apron to the fingers or projections 19 on the hubs attached to the shaft 8 and closes the developing-chamber by applying the cover portion. The continued rotation of the winding-shaft will then withdraw the apron 25 from the supporting-shaft 20, and the film or sensitized material will also be unwound from the cartridge and lie between the adjacent convolutions of the apron during the developing operation. The developing agent is preferably introduced into the developing-chamber A when the parts are in the position shown in Fig. 4, and the rotation of the operating or winding shaft is continued for the length of time required to complete the developing operation. When this is completed, the casing may be opened and the solution drained therefrom and the washing and fixing solutions supplied to the chamber, after which the apron may be withdrawn and the sensitized material removed therefrom.

A developing-machine such as I have shown and described embodying the supporting and operating shafts arranged in different chambers and the apron or support which is detachably connected to them permits the developing operation to be performed in a comparatively small chamber by a continuous operation of one of the shafts. It will be seen, further, that by forming the developing-chamber with the semicircular bottom conforming approximately to the apron when coiled a comparatively small amount of developing agents are required and that the solution is continuously agitated and every part of it is caused to circulate into contact with the sensitized material.

I claim as my invention—

55 1. In a photographic developing-machine, the combination with a casing, two shafts therein and an apron, of devices on the shafts adapted to detachably engage the ends of the apron whereby the latter may be unwound from either shaft and wound wholly upon the other, and means for supporting a spool of sensitized material in the casing.

2. In a photographic developing-machine, the combination with a casing, a receiving-shaft and a winding-shaft therein and an

apron, of detachable connections between said shafts and the ends of the apron operating when said shafts are revolved in opposite directions to wind said apron thereon, and means for supporting a spool of sensitized material in the casing. 70

3. In a photographic developing-machine, the combination with a casing, and an apron having engaging members at the end thereof, of a winding-shaft, hubs thereon and projections extending outwardly therefrom and adapted to engage the members on the apron when the shaft is revolved in one direction, means for operating it and devices for supporting a spool of sensitized material in the 80 casing. 75

4. In a photographic developing-machine, the combination with a casing, a flexible apron having a loop at its end and a bar extending through the loop and having engaging members at its ends, of a winding-shaft, projections thereon coöperating with said members, means for rotating the shaft and a device for supporting a spool of sensitized material in the casing. 85 90

5. In a photographic developing-machine, the combination with a casing, an apron, a winding-shaft and means for detachably connecting the apron to the shaft, of a device for supporting a spool of sensitized material in the casing and a rod arranged parallel to the shaft beneath which the end of the material on the spool may be secured. 95

6. In a photographic developing-machine, the combination with a casing, an apron and a shaft having hubs thereon, of fingers on the latter adapted to engage the end of the apron, a rod extending over the shaft and having the ends extending through the latter and the hubs and a device for supporting a spool 100 of sensitized material in the casing. 105

7. In a photographic developing-machine, the combination with a casing, an apron, having a cross-bar at its end and engaging devices attached to said bar, of a winding-shaft, hubs thereon adapted to receive the engaging devices and provided with recesses adapted to receive the bar, a device for supporting a spool of sensitized material in the casing and means for connecting the end of 115 said material to the winding-shaft. 110

8. In a photographic developing-machine, the combination with a casing, an apron and a winding-shaft connected thereto, of a device for supporting a spool of sensitized material in the casing and a rod arranged parallel to the shaft beneath which the end of the material on the spool may be secured and having the ends secured in apertures in said shaft. 120

9. In a photographic developing-machine, the combination with a casing, an apron and a shaft supporting the latter, of a revolute winding-shaft connected to one end of the apron, detachable connections between the 125 130

other end of the apron and the supporting-shaft whereby the apron may be automatically disconnected from the supporting-shaft when wound upon the winding-shaft and 5 means for supporting a spool of sensitized material in the casing.

10. In a photographic developing - machine, the combination with a casing having separable parts, one comprising an apron-holding chamber and the other an apron-receiving chamber, of a winding-shaft in each chamber, and a supporting device in the casing for holding a roll of sensitized material.

11. In a spool-holder for photographic developing-machines embodying a casing, the combination with a rod arranged therein and an arm guided on the rod, of a journal-pin on the arm adapted to support one end of a spool and a spring-operated bearing adapted 20 to support the opposite end of the spool.

12. In a spool-holder for photographic developing-machines embodying a casing, the combination with a rod supported in the casing in proximity to the side thereof, of an 25 arm guided thereon having a foot engaging the casing and provided with a journal adapted to support one end of a spool, and a relatively movable bearing for the other end of the spool.

30. 13. In a spool-holder for photographic developing-machines embodying a casing, the combination with a rod supported therein, an arm guided on the rod, of a journal on the arm adapted to support one end of a spool, a 35 journal-pin for the opposite end of the spool guided to move longitudinally in the casing

having the end located exteriorly thereof, a friction-head on said pin and a spring for moving the latter inwardly.

14. In a photographic developing - machine, the combination with a casing, and a cover portion coöperating therewith, of shafts journaled in the casing and cover portion, an apron adapted to be unwound from one shaft onto the other and means for supporting a roll of sensitized material in the casing.

15. In a photographic developing - machine, the combination with a casing forming a developing-chamber, having a recess 50 therein and a cover portion forming an apron-holding chamber and coöperating with the casing to close the developing-chamber, of a shaft arranged in each chamber, an apron adapted to be unwound from one shaft onto 55 the other and means for supporting a roll of sensitized material in the recess in the developing-chamber.

16. In a photographic developing - machine, the combination with a casing, a cover portion hinged thereto, the engaging portions of said casing and cover overlapping, of shafts journaled in the casing and cover portion, an apron adapted to be carried on the shaft in the cover portion and wound onto 60 the shaft in the casing and means for supporting a roll of sensitized material in proximity to the shaft in the casing.
